UNITED STATES PATENT OFFICE.

JOHN MURDOCH TEMPLETON, OF JOHANNESBURG, SOUTH AFRICA, ASSIGNOR TO
VACUUM OIL COMPANY, OF NEW YORK, N. Y., A CORPORATION OF NEW YORK.

LUBRICATOR FOR FLUID MOTORS.

Application filed December 7, 1925, Serial No. 73,555, and in South Africa December 5, 1924.

The present invention relates to lubricators for fluid motors such as jack-hammers, rock drills, riveters, stoppers, tie-tamers, etc., and an object of the invention is to provide a lubricator which will utilize the pressure in the fluid line leading to the motor for effecting the operation of the lubricator. A further object of the invention is to feed the lubricant to the fluid line under the pressure of the fluid line so that the fluid carries the lubricant into the fluid motor in an atomized condition.

To these and other ends, the invention consists of certain parts and combinations of parts, all of which will be hereinafter described: the novel features being pointed out in the appended claims.

In the drawings:—

Fig. 1 is a perspective view of an air pressure operated rock drill equipped with the present invention;

Fig. 2 is an enlarged sectional view through one embodiment of the lubricator, showing the piston in the position it occupies when the lubricator is filled with a lubricant;

Fig. 3 is a sectional view through another embodiment showing the position of the piston when the lubricator is filled with the lubricant;

Fig. 4 is a section of the embodiment illustrated in Fig. 3, showing the position of the piston when the lubricator is empty;

Fig. 5 is a longitudinal section through still another embodiment of the invention designed for use on jack hammers;

Fig. 6 is a sectional view through a jack hammer of known construction, showing the position of the lubricator;

Figs. 7 and 8 are sectional views through two other embodiments of the invention; and

Fig. 9 is an enlarged section on the line 9—9, Fig. 8.

Referring first to the embodiment illustrated in Figs. 1 and 2, 1 indicates a rock drill of known construction, which has an air line 2 connected thereto, preferably by a T 3, one arm of which connects with the air line 2, another arm of which connects with the intake of air motor of the rock drill, and another arm of which connects with the lubricator. The valve 2^a of the air line is arranged in advance of the T 3 so that air pressure to the lubricator is cut off with the stopping of the motor.

The lubricator as shown in the embodiment illustrated in Figs. 1 and 2 comprises a cylinder 4 having a removable head 5 at one end thereof secured by screws 6 and formed with a cylindrical projection 7 extending into the cylinder in spaced relation to the inner wall thereof to provide an annular space or chamber 8 at one end of the cylinder. The extreme end of the projecting portion of this head preferably carries a cupped packing 9 secured in place by a screw 10 and a disk 11. Within the cylinder a differential piston 12 operates, this piston being hollow to provide a skirt 13, which operates in the annular space 8, the cupped packing 9 cooperating with the inner face of the skirt and the lubricant chamber being formed at 14 between the end of the projection 7 and the inner face of the piston. The outer face of the piston opposed to the integral wall 15 of the cylinder has a packing preferably in cupped form as at 16 secured thereto by a screw 17 and a disk 18 so as to provide between the piston and the head 15 a chamber for the air. It is apparent that the effective pressure area of the piston exposed to the lubricant is less than that exposed to the air. As the skirt 13 moves back and forth it operates in the annular chamber 8, and in order to provide for free movement of the piston the head 5 has openings 19 communicating with said chamber 8. These openings also supply atmospheric pressure to the edge of the skirt 13 and this edge provides an area substantially equal to the difference between the effective pressure areas exposed to the air and the lubricant. Air is admitted to the air chamber preferably through a passageway 20 formed in the integral head 15 of the cylinder and through an externally threaded boss or attaching part 21 which projects from said head, and engages with an arm of the T 3, so that air may be admitted into the air chamber of the lubricator from the air line 2 to move the piston to expel the lubricant into the air line. If desired, as the piston reaches the limit of its expelling movement the air may be permitted to escape through one or more ports 22 formed in the wall of the cylinder and covered during the expelling movement of the skirt 13. The escape of air performs two functions, namely, signalling the user of the machine that the lubricator is empty and at the same time

slowing the action of the pneumatic motor. The first is secured by the whistling sound produced by the issuance of the air from the ports 22 and the second is secured by the reduction in pressure in the air supply, producing a retarding action of the motor and notifying the user that an additional lubricant is required.

The lubricant in this embodiment is fed 10 to the cylinder 14 through an opening closed by a plug 23 and this opening leads to a passageway 24 extending through the projection 7 of the removable head to the lubricant chamber 14. The lubricant flows from 15 the chamber 14 through the passageway 24 and port 25 in the head and through a passageway 26 in the cylinder leading to and through the boss or projection 21. If desired, a short tube 27 may connect with this 20 passageway and project into the T or connection 3, so that the air of the air supply pipe 2 flows past this tube or nozzle 27 and produces an atomizing effect on the lubricant issuing from said atomizing nozzle and 25 carries the oil into the air motor with the air supply. The amount of lubricant fed to the air motor may be controlled by a needle valve 28 at the junction of the ports 25 and 26, and operable from the exterior of the 30 cylinder.

In the embodiment shown in Figs. 3 and 4, the parts are the same except that there are slight differences in form and that the lubricant discharge leads through the piston head instead of through the projecting portion of the head of the cylinder. In this embodiment 4^a indicates the cylinder, 5^a the head, 7^a the projecting portion of the head, 8^a the annular cylinder between 35 the cylinder head and the main wall of the cylinder, and 9^a the cup packing on the cylinder head, secured by a plate 11^a and rivets 10^a. 12^a indicates the differential piston with the skirt 13^a movable in the annular 40 chamber 8^a which is open to the atmosphere through ports 19^a. The intake plug 23^a closes the filling opening and may be in the form of a valve through which lubricant 45 may be forced by a lubricant gun of any suitable type. The solid head 15 of the cylinder has a boss or projection 21^a through which the air inlet 20^a leads to the air chamber. From the lubricant chamber 14^a, two 50 passages or ports 24^a lead to a passage 26^a which is controlled by an adjustable needle valve 28^a. An atomizing tube 27^a connects with the passage 26^a and to the piston head 12^a and is guided in the externally threaded 55 projection 21^a. In all positions this tube 27^a projects preferably from the end of the projection 21^a. The valve 28^a in this instance, can be adjusted by removing the head 5^a or by removing the filling plug 23^a and cannot therefore be accidentally or 60 maliciously adjusted.

In the embodiment of the invention shown in Figs. 5 and 6 the lubricator is made a part of the pneumatic tool, which, in this instance, is a jack hammer. The lubricator is utilized as a handle for the tool. The 70 cylinder 4^b is elongated and the head 5^b is secured in place by a ring 6^b threaded internally and engaging external threads on the cylinder 4^b. This head has a shoulder 29 engaging the end of the cylinder and an annular shoulder 30 engaged by the ring. The projection 7^b of the head is elongated and is spaced from the interior wall of the cylinder at 8^b. A packing 9^b is carried by the inner end of this projection and the piston 12^b has an elongated skirt 13^b operating in the space 8^b, said piston carrying the packing opposed to the wall 15^b to provide the air chamber. The filling opening is closed by a valve plug 23^b and a lubricant outlet extends centrally through the head 7^b as at 24^b to a port 25^b. This port 25^b connects by a port 26^b with the part of the tool or motor to be lubricated. In this instance, the port 26^b leads through one of the supporting arms 29 to the cylinder 30 of the jack hammer. The other support 31 connects by a tubing 32 with the air supply 33 of the jack hammer. From this bracket 31 the air leads by a channel 20^b in the wall 95 of the cylinder 4^b to the air chamber of the lubricator. The control of the flow of the lubricant may be effected by an adjustable needle valve 28^b. A port 19^b serves to admit air to the chamber 8^b so as to subject the edge of the skirt of the piston to atmospheric pressure, and a port 22^b serves as a combined sight indicator and blow off. In this construction it will be noted that the lubricator acts as a handle for the jack hammer and the lubricant passage extends through one supporting arm or bracket of the handle to the motor of the jack hammer whereas the air passage leads through the other supporting arm or bracket from the 100 air supply to the handle or lubricator.

In the embodiment of the invention illustrated in Fig. 7, the cylinder 4^c has a head 15^c closing one end and the other end has an opening 8^c surrounded by a flange or sleeve 32. The piston 12^c has a packing 16^c on one side and a reduced portion or cylindrical plunger 13^c on the opposite side extending through and guided in the opening 8^c, a packing 9^c being secured to the walls of the opening of the cylinder 4^c to surround the projecting plunger 13^c and form a tight joint therewith. On one side of the piston 12^c a chamber 14^c is formed and on the opposite side of said piston a chamber for the air is provided which is received in such chamber through the port 20^c in the threaded projection 21^c. The plunger 13^c makes the effective area of the piston contacting with the lubricant less than that exposed to 105 110 115 120 125 130 135 140 145 150

the fluid pressure and this together with the fact that the end of the plunger is exposed to atmospheric pressure and provides an area substantially equal to the differences between the first two mentioned areas, causes the lubricant to be expelled. The lubricant is expelled through a passageway 26^c which connects with the atomizing nozzle 27^c on the externally threaded projection 21^c. In this 5 passageway an adjustable valve 24^c is mounted, the head of this valve being situated in the chamber 33 which is closed by a plug 34 so that malicious tampering with the valve 24^c is prevented. The lubricant is supplied 10 to the chamber 14^c by means of an axially extending passageway 35 in plunger 13^c having a lateral port 36, this passageway having at one end a valved filling plug 23^c with which a suitable grease gun may be connected. 15 This form of the invention has no audible alarm, but the sleeve 32 encloses the valved filling plug 23^c and is of such a length that when the lubricant chamber is empty, the valved filling plug which supplies the lubricant 20 will project from the sleeve 32 and acts as a visual signal.

In the embodiment of the invention shown in Fig. 8, the cylinder 4^d has at one end a closure 15^d and at the opposite end a closure 30 7^d. This cylinder has two bores 36 and 37 of different diameters. In the chamber formed by the bore 36 is a piston part 12^d carrying a packing 16^d, whereas in the chamber formed by the bore 37 is a piston 35 part 38 carrying a packing 9^d. These two piston parts are connected to form a differential piston by a tie member 39. Between the wall 15^d and the piston member 12^d, an air chamber is formed and this, through a 40 port 20^d, connects with the nipple or projection 21^d. The space between these two piston parts communicates with the atmosphere through a port 22^d which is so situated that piston part 12^d passes over it, to 45 permit air to escape from the air chamber. Between the piston member 38 and the wall 7^d a chamber 14^d is formed for the lubricant and this chamber through a port 26^d connects with the nozzle 27^d on the projection 21^d. This outlet from the lubricant 50 chamber 14^d is controlled by a screw valve member 24^d which has one side flattened to provide a passageway 40 through which the lubricant may reach the passageway 26^d. 55 This adjustable valve member 24^d lies opposite the plug opening 41 which when opened permits the valve to be adjustable. The chamber 14^d is filled through a lubricant plug 23^d secured in the closure 7^d and 60 normally covered by a cap 42.

In all embodiments of the invention, a motor driven by a compressed fluid from a compressed fluid supply is lubricated automatically through the means of a lubricator, 65 wherein a piston member substantially of the differential type is provided. This piston member consists of a single piece or a number of pieces jointed together so as to form a single operative member, one face of the piston member, being opposed to the compressed fluid and the opposed face, due to the differential construction, being exposed in part to the lubricant and in part to atmospheric pressure, thus producing a pressure on the lubricant greater than that in the compressed fluid. It is evident that this lubricator may be employed for machines operated by other compressed fluids than compressed air, so it will be understood that the invention is not to be limited to the use 70 of compressed air for effecting the movement of the differential piston. It is preferred, however, to use a fluid which is also used for propelling the motor to be lubricated so that one source of energy may be used for the two purposes. Preferably the lubricant is fed to the air supply and atomized by the latter so as to be carried into the motor with the air. It is apparent, however, that this is not necessary and that the lubricant can 75 be fed to any one or more parts of the motor requiring lubrication. Provision is made for signalling when the lubricating device is empty and for retarding the action of the motor when the lubricating device is empty. 80 Both of these results preferably are secured by the provision of a port which will act as a whistle and which will also permit the escape of air from the air supply, to reduce or to stop the action of the air motor. Preferably both the inlet for the air and the outlet for the lubricant are arranged at one end of the cylinder and extend through an externally threaded projection enabling the lubricating device to be readily attached to 85 a coupling member in the air line of a pneumatic motor.

What I claim as my invention and desire to secure by Letters Patent is:—

1. The combination with a fluid motor, of a fluid pressure operated lubricator for the motor connected with the fluid supply of the motor to be operated by said fluid supply and discharging in said fluid supply so that the fluid carries the lubricant to the motor, said lubricator having a fluid pressure exhaust port arranged to be uncovered automatically when the lubricant is exhausted to produce an audible signal and simultaneously slow the motor.

2. The combination with a fluid motor, of a fluid pressure operated lubricator for the motor comprising a cylinder, a head having a projection extending into the cylinder to provide an annular space, a piston providing a lubricant chamber between it and the head and having a skirt operating in the space between the projection and the inner wall of the cylinder and means for admitting fluid to the cylinder on opposite sides

120

125

130

- of the piston, said cylinder being provided with a fluid pressure exhaust port arranged to be covered by the piston when there is lubricant within the lubricant chamber and adapted to be automatically uncovered by the piston when the lubricant is exhausted, whereby the fluid pressure is permitted to escape to produce an audible signal and simultaneously slow down the motor.
3. In a lubricator of a type adapted to introduce regulated quantities of lubricant into a compressed fluid supply, the combination of a movable piston member having a plurality of piston faces, one piston face being actuated by the compressed fluid, an opposed piston face of lesser area being presented to the lubricant, and a similarly-directioned piston face of an effective area approximately equal to the difference between the two before mentioned areas, being presented to atmospheric pressure; a cylinder member, adapted to function with said piston mem-
- ber to form a compartment for compressed fluid and a compartment for lubricant, said cylinder compartments being of changing volume as the piston member moves, the cylinder member thereby functioning with said piston member to produce a pressure of lubricant greater than that of the compressed fluid; an inlet leading from the compressed fluid supply to the compartment for compressed fluid; and a lubricant discharge leading from the compartment for lubricant, said discharge leading to the compressed fluid supply, the cylinder being provided with an opening arranged to be automatically uncovered by the piston when the lubricant supply is exhausted and through which the compressed fluid may escape to produce an audible signal and slow down the motor to which the lubricator is connected.

In testimony whereof I have affixed my signature.

JOHN MURDOCH TEMPLETON.
